US00D740776S

(12) **United States Design Patent**
Kim et al.

(10) **Patent No.:** US D740,776 S
(45) **Date of Patent:** ** Oct. 13, 2015

(54) **MOBILE PHONE**

(71) Applicant: **LG Electronics Inc.**, Seoul (KR)

(72) Inventors: **Sungwoo Kim**, Gyeonggi-do (KR);
Hyunwoo Kim, Seoul (KR); **Woonlee Park**, Seoul (KR); **Joungyoung Joung**, Seoul (KR)

(73) Assignee: **LG Electronics Inc.**, Seoul (KR)

(**) Term: **14 Years**

(21) Appl. No.: **29/482,132**

(22) Filed: **Feb. 14, 2014**

(30) **Foreign Application Priority Data**

Aug. 20, 2013 (KR) 30-2013-0042746

(51) **LOC (10) Cl.** **14-03**

(52) **U.S. Cl.**

USPC ..... **D14/138 AD**; D14/138 G

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a perspective view thereof showing the state that the rear cover has been slid upward;

FIG. 10 is a front view of FIG. 9;

FIG. 11 is a rear view of FIG. 9;

FIG. 12 is a left side view of FIG. 9;

FIG. 13 is a right side view of FIG. 9; and,

FIG. 14 is a rear perspective view of FIG. 9.

The broken lines shown in the figures that are immediately adjacent to the shaded areas and define unshaded regions, represent the bounds of the claim, while all other broken lines are directed to environment; the broken lines form no part of the claimed design.

1 Claim, 13 Drawing Sheets
